CARL SCHAUM, OF PHILADELPHIA, PENNSYLVANIA, ASSIGNOR TO FLETCHER WORKS,
INCORPORATED, OF PHILADELPHIA, PENNSYLVANIA, A CORPORATION OF PENN-
SYLVANIA

REEL MECHANISM

Application filed January 30, 1930. Serial No. 424,436.

This invention relates to an improvement in reels and is particularly directed to the construction of the stop motion mechanism whereby the machine is stopped after a predetermined amount of thread has been skeined thereon, means also being provided whereby the machine will stop automatically upon the breaking of thread.

In the drawings accompanying this application:

Fig. 1 is a view in front elevation of a machine embodying my invention;

Fig. 2 is a view on the line 2—2 of Fig. 1;

Fig. 3 is a view on the line 3—3 of Fig. 1;

Fig. 4 shows the position of certain parts of the stop motion mechanism when the desired amount of thread has been skeined; and

Fig. 5 shows the position of certain parts of the mechanism assumed when a thread breaks.

Referring to the drawings in detail, 1 designates the fly and 2 the fly shaft. The fly shaft 2 extends lengthwise of the machine as will be seen from Fig. 1 and carries a plurality of spiders, two of these spiders having been shown in the drawings merely by way of illustration. The ends of the shaft are mounted in suitable bearings in the end frames of the machine designated 3 and 4.

At the left hand end of the fly shaft 2, as viewed in Fig. 1, is a friction disc 5 which is driven from a drive disc 6 mounted below the same, the disc 5 when the machine is in operation resting on the periphery of the drive disc 6. The drive disc is mounted on drive shaft 7 driven from any suitable source of power.

8 designates a brake arm pivoted to the end of the machine at 9. The free end of the brake arm 8 carries a roller 10 adapted to engage the upper face of a weighted control handle 11 pivoted at 12. The upper end of this control handle 11 is extended to the left, as viewed in Fig. 3, to provide an extension 13 to which is attached a rod 14, the lower end of which is attached to a foot pedal 15. Under certain conditions of operation depression of the pedal 15 to raise the rod 14 will release the brake 8 and swing the control

handle 11 into locked position as will be explained hereinafter.

16 designates a rocker shaft which extends longitudinally of the machine, while 16' designates a stop motion shaft which carries at its left hand end, as viewed in Fig. 1, a latching member 17. This latching member is provided with a latching notch near its upper end designated 18 which under certain conditions is adapted to cooperate with a pin 19 carried on the weighted control handle 11. About midway of the latch 17 and on the face thereof which is adjacent the pin 19 is a cam lug 20.

Extending lengthwise of the machine and mounted on suitable brackets 22 on rocker shaft 16 is a bar 21 having a rocking motion imparted to it by mechanism not shown, inasmuch as this construction is usual in machines of this general type.

The rocker shaft 16 and stop motion shaft 16' are mounted in brackets B.

The stop motion shaft 16' carries a plurality of upwardly extending brackets 23 which pivotally mount faller wires 24 each of these arms being provided at its outer end with a guide eye 25 through which the thread 26 from spools 27 is led upwardly to the fly 1, the thread passing through a guide eye 28 below the eye 25.

The stop motion shaft 16' is also provided with a weight lever 29 which normally tends to hold the stop motion shaft 16' and hence the brackets 23 in the position shown on Fig. 2.

Below the stop motion shaft and extending transversely of the machine, that is to say, inwardly beneath the drive shaft 7 is a pull rod 30 provided with an adjustable knock off collar 31 adjacent its outer end and at its inner end with a weight 32 pivotally attached thereto. The weight is mounted on a fixed pivot 32'. 33 designates the reset handle on the outer end of the pull rod 30. The weight is provided with a nose N adapted to cooperate with one arm of a weighted bell crank lever L. This lever is provided with a pin 34 adapted to be engaged by a pointer 35 which is adjustably carried on a count gear 36 and moves with said gear. This pointer 100

75

80

85

90

95

100

35 is made adjustable so as to vary the time at which the same will strike the pin 34 on the lever L, thereby enabling the amount of thread to the skein which is controlled by the 5 pointer, as will be pointed out, to be varied as desired. The lever L is provided for preventing the operator from stopping the machine before the full yardage for which the machine has been set has been reeled.

10 The drive for the count gear 36 is through a worm 37 mounted on a pivoted shaft 38 mounted above the gear and carrying at its other end, that is to say, on the opposite side of the pivot for the shaft from the worm 37 a 15 worm gear 39 meshing with a worm 40 on the fly shaft 2.

The shaft 38 is held in position to maintain the worm 37 in mesh with the teeth of the count gear 36 and the worm gear 39 in mesh 20 with the worm 40 by a latch 41.

Pivoted to the right hand end frame of the machine is a bell crank lever 42 pivoted at 43, one arm of this lever having a slot and pin connection 44 with the end of a connector 25 45 the other end of which is pivotally attached to the weight 32. The arm 46 of bell crank lever 42 is adapted to engage the latching finger 41 as will be presently described and also is provided with a lug 47 which is 30 adapted to engage a lug 48 on the shaft 38 so that when the bell crank is rocked about its pivot 43 to the dotted line position shown in Fig. 2 it will first unlatch or release the finger 41 and thereafter by engagement with 35 the lug 48 raise the left hand end of the shaft 38 to disengage the worm 37 from count gear 36 and worm gear 39 from worm 40.

In normal operation, that is to say, when the stop motion mechanism is to operate merely to stop the machine after a predetermined length of thread has been skeined, the count gear 36 driven from the fly shaft 2 will move in the direction of the arrow thereon until the pointer 35 which previously has been set 40 engages the pin 34 on the weighted bell crank lever L. This will cause the lever to be rocked to disengage its arm from nose N on the weight 32, and the latter thus being unlatched will rock to the right as viewed in 45 Fig. 2 about its pivot 32', dropping to the dotted line position of Fig. 2. In moving to this position the weight 32 will pull the connector 45 downwardly and thereby through the bell crank lever 42 move the worm 37 upwardly out of engagement with the count gear and simultaneously the worm wheel 39 out of engagement with the worm 40 on fly shaft 2.

This same movement of the weight 32 will 60 move the pull rod 30 inwardly of the machine, that is, to the left as viewed in Fig. 2 to the dotted line position shown therein and the knock off collar 31 will engage the extension 49 on the weight lever 29, so as to raise the weight 65 upwardly from the position shown in Fig. 2

and to rock the stop motion shaft 16' clockwise, as viewed in Fig. 2, anti-clockwise as viewed in Fig. 3. This motion of the stop motion shaft 16' will, as will be understood, rock the latch 17 to the left from the position shown in Fig. 3, so as to pull the notch 18 therein away from the latching pin 19 on the control handle 11 and permit the latter to drop. This condition is illustrated in Fig. 4. The dropping of the control handle 11 will raise the brake arm 8 upwardly to carry the friction disc 5 away from the face of the drive disc 6 and apply the brake. The machine, therefore, is now at rest.

The parts remain in this position until the 25 machine is ready to be set into operation again, whereupon it is necessary first to reset the pull rod 30 which is done by grasping the handle 33 and pulling the rod toward the front of the machine. This will restore the 26 weight 32 to its original position, the nose N slipping past the arm of bell crank L, and restore the shaft 38 to its original driving position, that is, with the worm 37 in engagement with the face of the count gear 36 and the worm gear 39 in engagement with the worm 40 on the fly shaft 2.

Movement or resetting of the rod 30 will also permit the counterweight 29 to drop to its original position, which will rock the stop motion shaft 16' clockwise as viewed in Fig. 4, to impart a corresponding movement to latching member 17, to permit the control member 11 again to be raised into the position of Fig. 3, this return movement being prevented until the rod 30 is reset by the lug 20 on the latching member 17 which as shown in Fig. 4 moves into the path of the pin 19 on control member 11 when the machine trips.

It is now merely necessary to depress the 10 foot pedal 15 to raise the control member 11 to latched position, this same operation removing the brake 8 and permitting friction disc 6.

The description thus far given of the stop motion mechanism is normal. I will now give a description of operation when a thread breaks in the machine, at which time it is desired to stop the machine automatically and as the thread may break at any time during the operation of the machine it is to be understood of course that the pointer 35 on the count gear 36 cannot be relied upon for this purpose.

As previously described, the threads 26 are threaded through eyes 25 on faller wires 24. These faller wires are so mounted in brackets 23 that in the event of a thread breaking the wires will fall to the left, as viewed in Fig. 2. In this event the bar 21 which it will be remembered is given an oscillatory or rocking movement toward and away from the front of the machine engages the lower end of the mount 51 which carries the faller wire corre- 125 130

sponding to the broken thread. The effect of this is to again raise the weight 29 as occurred when the count gear 36 functioned to stop the machine and to at the same time rock the stop motion shaft 16' clockwise, as viewed in Fig. 2, and anti-clockwise, as viewed in Fig. 3, with the result that the latch 17 will be moved out of locking position, the controller arm 11 will fall, raise the friction pulley 15 from the face of the driving disc 6 and apply the brake 8 and the machine again will come to rest.

As soon as the controller arm 11 falls the latch 17 will move back to its extreme right hand position again, as shown in Fig. 5, under the action of the weight 29 instead of remaining in its outward position as it did when the count gear operated, the rod 30 having remained in set position so that the collar 31 is in inoperative position, and consequently the cam lug 20 will lie out of the path of the pin 19 on latching member 11. After the broken thread is tied the operator by merely depressing the foot pedal can again start the machine in operation.

It will be seen from the foregoing, therefore, that I have provided a reeling machine in which the control member 11 is retained in operative position unless released by the measuring or count wheel 36, and that means are provided for resetting the machine until the measuring device is reset.

It will be seen also that I have provided a construction whereby tripping of the machine to stop the same deliberately before the full yardage is reeled is prevented.

It is to be understood that changes may be made in the details of construction above described within the purview of my invention.

What I claim is:

1. In a stop motion the combination of a stop motion shaft, a weight lever attached thereto, and weight-actuated mechanism for rotating the stop motion shaft against the action of said weight lever.

2. In reeling mechanism the combination of a stop motion shaft, a weight lever attached thereto, a weight, latching mechanism for said weight, and a rod connected to said weight and operatively connected to said weight lever operable upon release of said weight to rock said stop motion shaft against the action of the weight lever carried thereby.

3. In reeling mechanism the combination of a stop motion shaft, a weight lever attached thereto, a weight, latching mechanism therefor, a rod attached to said weight, and a knock off collar carried by said rod and cooperable with the weight lever to impart a rotary movement to the stop motion shaft.

4. In reeling mechanism comprising a reel shaft, and a count gear, the combination of gearing intermediate said reel shaft and count gear for imparting movement from the

reel shaft to the count gear, a pivoted shaft carrying said gearing, and a weight operative at a predetermined time for pivoting the gear shaft to disconnect the drive between the reel shaft and count gear.

5. In reeling mechanism comprising a reel shaft and a count gear, the combination of a shaft intermediate said reel shaft and count gear, gearing carried by said shaft for providing a drive from the reel shaft to the count gear, a weight, latching mechanism therefor, releasing mechanism for said latching mechanism to permit said weight to fall, and a connection between said weight and the gear shaft to move said shaft to position to break the driving connection between the reel shaft and count gear upon operation of said weight.

6. In reeling mechanism comprising a count gear, the combination of a pivoted driving shaft for the count gear, a weight, latching mechanism for said weight, and a connection between said weight and said shaft to effect a predetermined release of said weight to move said shaft to inoperative position.

7. In reeling mechanism comprising a count gear, the combination of a driven pivoted shaft, count-gear driving gear mechanism carried by said shaft, a latch for holding said shaft in operative position, a weight, a latch for said weight, and a connection between said weight and said first-mentioned latching mechanism and said shaft for releasing said first-mentioned latching mechanism and moving said shaft to inoperative position.

8. In reeling mechanism comprising a count wheel, the combination of a pivoted gear shaft for driving the count wheel, a weight, a pivoted weighted lever for holding said weight in operative position, means for moving said weighted lever to inoperative position to release said weight, and connections between said weight and said shaft operative upon unlatching of the weight to effect a movement of said shaft to inoperative position.

9. A stop mechanism for reeling machines comprising a control lever, a latch therefor, and a plurality of releasing means for said lever, one of said means positioning the latch to prevent movement of the control lever to operative position, the other means positioning the latch to allow the control lever to be moved into operative position.

10. A stop mechanism for reeling machines comprising a control lever, a latch for said control lever, said latch retaining the control lever in operative position under predetermined conditions and retaining the control lever in inoperative position under different conditions.

11. In reeling mechanism the combination of a control lever, a latch therefor, said latch

70

- normally retaining the control lever in operative position, means for maintaining the latch in position to prevent resetting of the control lever under predetermined conditions, and faller wires operable upon breakage of a thread to effect movement of the latching mechanism to a position where it may be reset upon restoring of the thread and movement of the faller wire to its original position.
12. In a stop motion for reeling machines comprising a measuring device, the combination of a control lever for establishing a driving connection for the machine, latching mechanism for holding said lever in operative position, and a cam carried thereby, said cam being so positioned with respect to the latching mechanism as to prevent resetting of the control lever to establish a driving connection to the machine unless the measuring device has been reset.
13. In a stop motion mechanism for reeling machines comprising a measuring device, the combination of a control lever for establishing a driving connection to the machine, a latch for said control lever, a cam carried by said latch mechanism, connections between the measuring device of the machine and said latch mechanism to move the latch upon predetermined movement of the measuring device to a position to bring said cam into stopping relation with respect to said control lever to prevent resetting of the control lever until the measuring device has been reset, means operative upon breakage of a thread to release said latching mechanism, and means operative upon the last-mentioned release of the latching mechanism to move the same into position whereby the cam is carried out of stopping relation with the control lever whereby upon restoring of the thread the control lever may be moved to latched position without resetting the counting mechanism.
14. In reeling mechanism the combination of a stop motion shaft, a weight lever attached thereto, a weight, a latch for said weight, mechanism for releasing said latch, a pull rod attached to said weight and manually operable to restore the weight to initial position after its release by said releasing mechanism, and a knock off collar carried by said pull rod and operable upon actuation of the rod to raise the weight lever and impart corresponding movement to the stop motion shaft.
15. In a stop motion for reeling machines having a count gear, the combination of count gear driving mechanism, a lever pivoted intermediate its ends and adapted to move said driving mechanism out of driving position, a weight for actuating said lever, and a connector between said weight and lever having pivotal connection with the weight and a slot and pin connection with said lever.
16. In a stop motion the combination of a driven disc, a drive disc, control mechanism for moving the driven disc out of driven position relatively to the drive disc, a latch for holding said control mechanism out of operating position, a stop motion shaft carrying said latch, and a weight for imparting rotary movement to said stop motion shaft to move the latching mechanism out of latching position thereby to permit the control mechanism to operate and to move the driven disc out of driven position relatively to the drive disc.
17. In a stop motion the combination of a driven disc, a drive disc therefor, control mechanism for moving the driven disc out of operative position relatively to the drive disc and to apply a brake to the driven disc, a latch member for holding the control mechanism in inoperative position, a stop motion shaft carrying said latching member, a weight lever on said shaft, and a weight operatively connected to said weight lever and adapted upon actuation to move the weight lever and stop motion shaft thereby to carry the latching member out of latching position relatively to the control mechanism.
18. In a stop motion the combination of a driven disc, a drive disc therefor, control mechanism for moving the driven disc out of operative position relatively to the drive disc, a latch member for preventing actuation of the control mechanism, a foot pedal for restoring the control mechanism to initial position after release of the latch member, a weight for releasing said latch member, manually operable means for restoring said weight to operative position, and means for preventing movement under predetermined conditions of the control mechanism to latched position by operation of the foot pedal.
19. In a stop motion the combination of a driven disc, a drive disc, control mechanism adapted when actuated to move the driven disc out of driving position relatively to the drive disc, a latch member for latching said control mechanism out of operating position, a foot pedal for restoring the control mechanism to latched position, and means carried by the latch member and cooperable with the control mechanism for preventing restoration of the latter to latched position under the action of the foot pedal under predetermined conditions.
20. In a stop motion the combination of a control member, a latch member therefor, mechanism for effecting movement of the latch member to inoperative position, a foot pedal for restoring said control member to latched position, and a lug carried by the latch member and cooperable with the control member to prevent foot-pedal-restora-

tion of the control member under predetermined conditions.

21. In a stop motion the combination of a control member, a latch member therefor, a stop motion shaft carrying said latch member, a weight lever carried by said shaft, a faller wire operatively attached to said shaft, and means operable upon the breaking of a thread connected to said faller wire to rock said shaft against the resistance of said weight to release the latch member.

This specification signed this 27 day of January, 1930.

CARL SCHAUM.
